UNITED STATES PATENT OFFICE.

MORGAN WILLIAMS, OF OGMORE VALE, NEAR BRIDGEND, WALES.

PIT-CAGE ARRESTER.

Application filed November 20, 1922. Serial No. 602,182.

To all whom it may concern:

Be it known that I, MORGAN WILLIAMS, a subject of the King of Great Britain and Ireland, and a resident of Ogmore Vale, 5 near Bridgend, county of Glamorgan, Wales, have invented a certain new and useful Improvement in Pit-Cage Arresters, of which the following is a specification.

This invention relates to a pit-cage ar- 10 rester or safety device of the kind consisting of rack and pinion means co-acting with spring-actuated means to lock the pinion with the teeth of the rack on the breaking of the winding cable, thus preventing the 15 downward movement of the cage, the rack extending the length of the shaft and separate from the cage, the spring-actuated means being mounted on top of the cage.

In the above construction the pinion was 20 shrouded and provided on each side with a ratchet wheel with which, on the breaking of the winding cable, and under the combined action of a spring and the weight of the lifting shackle or ring, engaged the 25 wedge-shaped front end of a pivotally mounted lever, the shackle pressing on the tail end of said lever, the spring pressing on the front end thereof, preventing rotation of the ratchet wheels, thus locking the pinion 30 to or with the teeth of the rack, consequently arresting the downward movement of the cage.

According to the present invention, the device, of which two are employed with 35 each cage, comprises a shrouded pinion, rotatably mounted on the roof of the cage and provided on each shroud with a rhomboidal-shaped plate formed in one with said shroud, or rigidly affixed thereto, and a vertically disposed rack or toothed bar located at the side of the cage and between the usual conductors, said rack or toothed bar extending the depth of the shaft. On the roof of the cage there is slidably mounted 40 an horizontally disposed spring-pressed bar connected by cable to the ring of the winding rope, the arrangement being such that in the event of the breaking of or the unforeseen slackening of the winding cable, 45 the horizontally disposed slidable bar moves forward and engages the rhomboidal-shaped plates on the pinion, stopping the rotation of said pinion, consequently locking the same to or with the teeth of the rack, thus 50 preventing the downward movement of the cage.

In order that the invention may be clearly understood, reference is to be had to the following description and accompanying sheets of drawings, wherein:—

Figure 1 is a plan; and,

Figure 2 a vertical sectional view illustrative of the invention, winding cable taut.

Figures 3 and 4 are similar views, but showing the arrester in action.

Figure 5 is a view of one of the shrouded pinions.

Like letters of reference indicate corresponding parts in the several figures.

In carrying out the invention and refer- 70 ring to the drawings, *a*, *a* are two vertically disposed racks or toothed bars, located one at each side of the cage *b* and extending the depth of the shaft, *b*¹, *b*¹ are the usual conductors, and *b*² the lifting chains connected 75 to the winding cable *b*³.

Rotatably mounted in brackets *c* on the roof of the cage *b* are the shrouded pinions *c*¹, *c*¹, one of which is shown separately in Figure 5, and which engage with the racks 80 *a*, *a*, the shrouds *c*² of said pinions *c*¹ being of a depth such as to cover said racks and each provided with a rhomboidal-shaped locking plate *c*³.

Slidably mounted between horizontally 85 disposed bars *d* fixedly secured to the roof of the cage *b* are two locking bars *e*, said bars *e* also sliding on rods *d*¹ fixedly carried by transversely disposed bars *d*² secured to the bars *d* aforesaid, coiled springs *d*³ encircling the rods *d*¹ being interposed between each locking bar *e* and the inner fixed bar *d*².

Through each central spring *d*³ there ex- 95 tends a wire, cable or the like *f* which is secured at one end to its slidable bar *e* whilst the other end of said wire, cable or the like *f* is passed through a hole in the rear fixed bar *d*² to and round a pulley *f*¹ mounted on the roof of the cage *b* and up to the shackle 100 or link connecting the lifting chains *b*² with the winding cable *b*³.

The arrangement is such that, as long as the winding cable remains taut, parts are in the position shown in Figures 1 and 2, the 105 bars *e* being drawn back clear of the locking plates *c*³ of the pinions *c*¹, allowing the same to freely rotate as the cage moves up and down, but when said winding cable breaks, the bars *e*, under the action of their 110 springs *d*³, fly outwardly into engagement with the locking plates *c*³ of said pinions *c*¹.

as shown in Figures 3 and 4, arresting the rotation of said pinions, holding the same rigid, thus locking said pinions with the racks a , a , thus arresting the downward movement of the cage b .

I claim:—

1. A pit-cage arrester of the class described including in combination with the winding cable, a pinion provided with an angular locking plate, a slidable locking bar arranged at one side of the pinion, springs for shifting said bar toward the pinion, and a connection between said bar and the winding cable operable upon the break of the winding cable to release said locking bar to permit the springs to shift it into locking engagement with the pinion.
2. A pit-cage arrester of the class described including in combination with the lifting shackle of the winding cable, a pinion provided on each side with a rhomboidal-shaped plate, a horizontally disposed slidably mounted spring-pressed locking bar arranged at one side of the pinion, and a connection between said bar and the lifting

shackle whereby upon the breaking of the winding cable the bar may be shifted into engagement with said rhomboidal-shaped plate.

3. A pit-cage arrester of the class described including opposite horizontally disposed guide bars mounted on the roof of the cage, transverse bars between the guide bars, rods mounted parallel to the guide bars and slidable in the transverse bars, a locking bar carried by one end of said rods, springs on said rods for engaging the locking bar, a pinion having rhomboidal-shaped side plates, a pulley supported at the central part of the cage, a cable connected with the locking bar and passing over said pulley to engage with the lifting shackle to thereby normally hold the locking bar against the tension of said springs and out of the path of movement of the rhomboidal-shaped plates carried by the pinion.

In testimony whereof I have affixed my signature hereto this 6th day of November 1922.

MORGAN WILLIAMS.
